3,015,001 SWITCH ASSEMBLY

Robert C. Woofter, Cortland, Ohio, assignor to General Motors Corporation, Detroit, Mich., a corporation of Delaware

Filed Dec. 11, 1958, Ser. No. 779,780
1 Claim. (Cl. 200—16)

This invention relates generally to switch assemblies and is particularly adapted for use with various combinations of energizing and holding circuits. The invention will be described in connection with the circuitry for energizing electromagnetically-operated clutch assemblies used on automotive and other types of vehicles to establish and hold a throttle in any desired open position. While the switch assembly set forth herein is particularly adapted for the type of application set forth herein, it will be appreciated that there are many other applications for such a switch too numerous to mention.

One of the primary objects of the invention is to provide a switch assembly which has three operating positions: One in which no contacts are closed, a second in which two sets of contacts are closed and an intermediate position in which only one set of contacts is closed.

A further object of the invention is to provide biasing means in the assembly which when the switch is in one of its operating positions urges the contacts thereof toward another position. More specifically, when the contacts of the switch are in the operating position in which all of the sets of the contacts are closed it is being urged toward a position in which only part of the sets of contacts of the switch is closed.

For a fuller understanding of the invention and the above and other objects thereof, reference may be made to the accompanying detailed description and drawings in which:

FIGURE 1 is a view in plan of the upper side of the switch assembly having superimposed thereon a schematic diagram representing circuitry of the type used to control and operate the throttle hold devices for trucks, automotive and other types of vehicles.

FIGURE 2 is a side elevational view taken substantially on the line 2—2 of FIGURE 1 with parts in section and broken away to illustrate many of the internal details of construction of the switch.

FIGURE 3 is a view looking down on the switch taken substantially on the line 3—3 of FIGURE 2 further illustrating internal details of construction of the switch assembly.

FIGURE 4 is a view taken substantially on the line 4—4 of FIGURE 1.

FIGURE 5 is a view taken substantially on the line 5—5 of FIGURE 3 illustrating the manner in which the operating rod of the switch is secured to the movable contact carrier of the switch.

FIGURE 6 is a view looking upwardly taken on the line 6—6 of FIGURE 2 and shows the intermediate position of the contact carrier of the switch in which only one set of the switch contacts is bridged.

Turning now to the drawings, the switch assembly includes an outer box or housing 2 comprising an upper side 4, two sides 6 and 8 and ends 10 and 12. The box or housing 2 is closed by a lower cover plate 14 which is secured to the housing 2 by studs 16. The box 2 and cover 14 form an inner elongated chamber 18 in which is movable back and forth a contact carrier block 20. The block 20, which is made of some suitable insulating material, is provided with two longitudinally extending recesses 22 and 24 side by side which contain bridge contactors 26 and 28, respectively, both supported at opposite ends thereof by small helical coil springs 30.

2

Fixed in the upper side 4 and flush with the inside surface 32 of upper side 4 are two sets of longitudinally spaced contacts 34, 36 and 39, 40, respectively. The sets of contacts 34, 36 are adapted to be bridged by the bridge contact 26 and the sets of contacts 38, 40 are adapted to be bridged by the bridge contact 28. The contacts 34, 36, 38, 40 are provided with suitable shanks 42 which extend through the upper side 4 and have bifurcated ends 44 to anchor suitable terminals 46, 48, 50, 52, respectively. 10 A second recess 54 is provided in the lower part of the contact carrier block 20 in which is located a helical coil spring 56 and a pair of washers 58, 60, all of which are mounted on a rod 62 extending through the recess 54 to the opposite ends 10 and 12 of housing 2. The rod 62 is pinched at the points 64 and 66 so as to limit the movement of spring 56 between these two points. The washer 58 abuts an end wall 68 of the recess 54 of carrier 20 thereby urging the carrier to the left as viewed in FIGURE 2 under the influence of spring 56. Extending through the end wall 12 of housing 2 is an operating rod or bar 70 having an operating handle 72 threaded on one end thereof. The bar 70 extends into a third recess 74 in carrier 20 and has a reduced portion 76 which is in alignment with a cut-out portion 78 of recess 74. A spring retainer 80 has one end snapped over a shoulder 82 of carrier 20 and extends from adjacent one side of the carrier to the other through the space provided by the necked-down portion 76 so as to fasten the operating rod 70 to carrier 20. The spring retainer 80 which is 25 U-shaped in configuration is provided with a leg and foot 84 which is adapted to be engaged by a small spring biased plunger 86 to thereby depress the spring retainer 80 and release the operating rod 70 from its connection to carrier 20. 30 Turning again for a moment particularly to FIGURES 1, 2 and 3, the cover plate 14 extends below the end 12 of housing 2 and is provided with a boss portion 88 having internal threads in which is threaded a bushing 90 forming a slide bearing for rod 70. 35 Referring now to FIGURE 1, a circuit has been superimposed on this view of the switch assembly and includes a battery 92 having one end grounded and the opposite end connected to a switch 94. A second switch 96 which is normally closed but opens in response to vehicle brake 40 45 pedal 98 immediately precedes connection of one of the contacts of switch 96 to the terminal 46 of the switch assembly. An electromagnet which is symbolically shown by the coil 100 has one end grounded and the opposite end connected by a conductor 102 to terminal 50. The electromagnet 100 is shown as controlling a switch 104 located between electromagnet 100 and terminal 52. Terminals 48 and 52 are connected together by a conductor 106. The electromagnet 100 may be used in devices which are adapted to maintain the throttle of a 50 55 vehicle in any desired open position to clutch the throttle or a part of its linkage to any suitable support so that the throttle cannot be moved with respect to whatever position it may be in at the time of energization of electromagnet 100. The operation of the switch assembly is 60 65 70 as follows: Assuming that an operator of a vehicle has his throttle in a certain desired open position and he wishes to maintain the throttle in this position so that he can remove his foot from the throttle pedal, he would grasp the handle 72 and pull it to the right or outwardly as viewed in FIGURES 1 and 2 until an end 108 of carrier 20 abuts a shoulder 110. When the carrier 20 is moved to this extreme position to the right as viewed in FIGURES 2 and 3, the spring will be compressed between the point 66 and the end wall 68 of carrier 20. In this extreme position the bridge contactors 26, 28 will bridge their associated sets

of contacts 34, 36 and 38, 40. Assuming switch 94 and brake switch 96 to be closed, current may now flow from the battery 92 through switches 94 and 96, through terminal 46, across the bridge contactor 26, through terminal 48, conductor 106 to terminal 52, through the bridge contactor 28 to terminal 50 and through conductor 102 to electromagnet 100 thereby energizing the electromagnet. When electromagnet 100 is energized it will close switch 104 so that current may also now flow from the battery 92 through switch 94, 96, across terminals 46, 48, through bridge contactor 26, through conductor 106, through terminal 52, conductor 112 and switch 104 to electromagnet 100 thereby maintaining it energized. If now the handle 72 is released the carrier 20 will be moved to the left as viewed in FIGURE 2 to the position shown by action of the spring 56. In this position bridge contactor 28 will no longer bridge its contacts 38, 40 as indicated in FIGURES 2 and 6. Contacts 34, 36, however, will remain connected together by their bridge contactor 26 so that electromagnet 100 may be maintained energized by the circuit last traced out. If the operator should now depress the brake pedal 98 it would be undesirable to have the throttle remain in this open position. Accordingly, depression of brake pedal 98 will open switch 96 thereby breaking the circuit through the switch and deenergizing electromagnet 100. Deenergization of electromagnet 100 will open switch 104 so that now the only way that the throttle hold circuit can be reenergized is to again pull the handle 72 to the right as viewed in FIGURE 2 to reestablish energization of the electromagnet 100 in the manner previously described. The operator can render the throttle hold device inactive merely by pushing the handle 72 until the wall 68 of the contact carrier 20 engages a shoulder 114 of housing 2. Neither bridge contacts 26 nor 28 will then engage the associated contacts 34 and 36 or 38 and 40, respectively.

From the foregoing description it will be appreciated that a unique switch assembly has been described which has unusual operating characteristics. In its first position, none of the contacts of the switch are electrically con-

nected together. In a second position all of the contacts are connected together, and in a third position to which the movable contacts of the switch are urged when in the second position only part of the contacts are electrically connected together. The switch is particularly adapted for applications of the type used as an example here.

I claim:

A switch assembly comprising an insulated housing having a longitudinal recess therein receiving a contact carrier block, a first pair of contacts in said housing and extending into said recess in generally longitudinal alignment with said recess and a second pair of contacts in said housing in generally parallel alignment with and transversely offset from said first pair of contacts, first and second contact bridging members mounted on said carrier block for engaging and bridging the contacts of each of said contact pairs, said carrier block being movable to a first position so that neither of said bridging members bridge said contacts and normally positioned in a second position wherein one of said bridging members bridges one of said contact pairs and movable to a third position wherein each of said bridging members bridge one of said contact pairs, a carrier control rod extending through one end of said housing, and spring means mounted on said carrier and locking said control rod to said carrier whereby said control rod may move said carrier to each of said positions, said spring being movable to disengage said rod from said carrier.
